CLAIM

The ornamental design for a solar panel optic, as shown and described.

DESCRIPTION

FIG. 1 is a top plan view of a solar panel optic according to our design;

FIG. 2 is a bottom plan view of the solar panel optic of FIG. 1;

FIG. 3 is a right side elevation view of the solar panel optic of FIG. 1, the left side, front and rear elevation views being identical thereto;

FIG. 4 is a top, front, and right side perspective view of the solar panel optic of FIG. 1, the top, rear, and left side perspective view being identical thereto;

FIG. 5 is a bottom, front, and right side perspective view of the solar panel optic of FIG. 1, the bottom, rear, and left side perspective view being identical thereto;

FIG. 6 is a cross-section view of the solar panel optic of FIG. 1 taken along the line 6-6 in FIG. 1;

FIG. 7 is a perspective view of the cross-section of the solar panel optic shown in FIGS. 6; and,

FIG. 8 is a perspective view of the solar panel optic of FIG. 1 shown in environmental use.

(Continued)

The broken lines shown represent unclaimed subject matter and form no part of the claimed design.
